Primary Examiner — Robin V Webster*Assistant Examiner* — Keith J Wilson(74) *Attorney, Agent, or Firm* — Jacobson Holman, PLLC.(57) **CLAIM**

I claim the ornamental design for a magazine for a toy gun, as shown and described.

DESCRIPTION

FIG. 1 is a front perspective view of a magazine for a toy gun according to my design;

FIG. 2 is a bottom perspective view of FIG. 1;

FIG. 3 is a left side elevational view of FIG. 1;

FIG. 4 is a right side elevational view of FIG. 1;

FIG. 5 is back elevational view of FIG. 1;

FIG. 6 is a front elevational view of FIG. 1;

FIG. 7 is a top plan view of FIG. 1; and,

FIG. 8 is a bottom view of FIG. 1.

The broken lines in the drawings illustrate portions of the magazine for a toy gun that form no part of the claimed design.
